UNITED STATES PATENT OFFICE.

EDWARD MURBY, OF ST. LOUIS, MISSOURI.

MACHINE FOR MAKING LOOPED FABRIC.

SPECIFICATION forming part of Letters Patent No. 521,728, dated June 19, 1894.

Application filed February 24, 1894. Serial No. 501,433. (No model.)

To all whom it may concern:

Be it known that I, EDWARD MURBY, of the city of St. Louis, in the State of Missouri, have invented a certain new and useful Improvement 5 in Machines for Making Looped Fabric, of which the following is a full, clear, and exact description, reference being had to the accompanying drawings, forming part of this specification.

10 My present invention relates to machines for knitting fabric and simultaneously forming thereon a series of loops which are knitted into the fabric and form a part thereof.

15 My machine is particularly intended for making harness pads, such as are shown and described in my contemporaneous application, Serial No. 501,432, filed February 24, 1894.

20 My present invention consists in features of novelty hereinafter fully described and pointed out in the claims.

Figure I is a plan view, illustrative of my improved machine, the dial shaft being shown in section. Fig. II is a detail, side elevation. Fig. III is a detail, vertical section. Fig. IV 25 is a detail, vertical section, showing the loop points withdrawn from working position. Fig. V is a detail, perspective view. Fig. VI is a detail, vertical section with the loop points in their outer or working position. Figs. VII 30 and VIII are detail, top views. Fig. IX is a diagram.

Referring to the drawings, 1 represents the needles of an ordinary machine, their arrangement and mode of operation being well understood, and require no explanation here.

35 2 represents a dial plate carried on a shaft or rod 3, and adapted to rest within the needle cylinder, or to be removed therefrom, as shown in my patent, No. 407,960, issued July 40 30, 1889.

In my improved machine, the dial 2 has a number of fixed points 4, projecting from its periphery, each point having preferably a recess 5 in its outer end.

45 In the operation of the machine, the dial turns with the needle cylinder, its movement being caused by ears thereon, which engage with projections on the inner face of the needle cylinder, as in the patent. As the dial 50 revolves, the points 4 catch one thread of the yarn, as shown in Figs. V and IX, and by holding this yarn back, a loop is formed by

each point, thus producing a fabric having a series of projecting loops, as shown in my application referred to.

55 The points 4 being stationary, it becomes necessary to devise some means of dislodging the loops from the points, as the dial revolves. This is accomplished by an inclined finger 6, secured to the frame of the machine, and the inner end of which is just beneath the path of the points 4, as shown in Fig. V, so that as the cylinder turns, the loops are dislodged from the points 4, by coming in contact with the finger 6. The manner in which the yarn is caught by the points 4, between the needles 1, is illustrated in Fig. 60 IX, the yarn being drawn over the points, and not being dislodged therefrom by the finger 6 until after the stitch is formed.

65 For plain work, in one direction, it is not necessary for the finger 6 to be moved, but if it is desired to narrow the work, by turning the machine in the opposite direction, then it is necessary to provide two of the fingers 6, as shown in Fig. I, and it is also necessary to provide for the outward movement of the finger, which is inactive for the time being, in order that this finger will not interfere with the operation of the machine, so 70 that when it is desired to use the machine on work which has to be narrowed, I mount the fingers 6 on shafts or rods 7, secured by plates 8 to the frame 9, within which the needle cylinder fits.

75 10 represents springs surrounding the shafts or rods 7, and the tendency of which is to hold the fingers 6 to their inner positions, the inward movement of the fingers being arrested by stops 11 secured to the upper ends 90 of the rods or shafts 7; the stops having downturned ends against which the plates 13, carried by the fingers 6 impinge. The plates 13 and fingers 6 are connected by a hub 14, so as to move together, the hub fitting 95 loosely on the shafts 7.

14 represents the yarn or thread guide, carried by the spindle or shaft 3, and which is swung from side to side during the narrowing process, and as this guide comes against 100 the outturned end 15 of the plate 13, it moves the plate and finger out of the path of the points 4. The plate and finger are shown moved to their outer position on the right

side of Fig. I. When the guide 14 is thrown over to its other position, the plate and finger, which are now shown as held out by the guide, move to their inner position against the stop 11, and as the guide reaches the other side of its throw, it moves the other plate 13, and finger 6 out of working position.

The construction and operation of the guide 14, *per se*, as well as the construction and operation of the stationary guide 17, are well understood in knitting machines, and need no explanation. They have nothing to do with my present invention, except so far as the movable guide 14 acts to throw the finger 6 out of working position, and as I have already stated, the finger 6 may be fixed and stationary, if only plain work is to be done on the machine, and of course only one will be required.

I have stated that the points 4 are fixed or stationary; what I mean by this expression is that they do not move in and out during the operation of the machine, but I have provided means whereby they may be moved inwardly and held in this inner position when it is desired to do plain work on the machine, that is to knit without forming loops. The mechanism I have shown for accomplishing this result is to form heads 20 on the inner ends of the points, and surround these heads by a spring 21, the form of the spring being shown in Fig. I.

22 represents a collar fitting over a ring 23 on the shaft 3. This collar bears at its lower end against the heads 20 of the points, and is held to its adjustment by a set screw 24 fitting in a bayonet slot 25 in the collar. When the collar is in its lower position, the points 4 are forced to their outer or working position, and are held in this position by the collar. They do not move out and in during the operation of the machine, but are held fixed in either position. If it is desired to do plain work, the collar 25 is raised, as shown in Fig. IV, and the spring 21 draws the points 4 in out of working position, or out of a position where they will catch the yarn to form a loop, and then the machine may be used as an ordinary knitting machine 50 without the loops being formed.

In Fig. V I have shown the points 4 as simply inserted into the dial plate, and this may be done where it is not desired to knit plain work upon the same machine as is used for forming looped work.

It is evident that the form of the springs 10 may be varied without departing from the spirit of my invention.

The plates 13, it will be noticed, have a flat surface 13^a on their inner faces. The object of this flat surface is to receive those needles 1 which are elevated (when doing heel and toe work) as they are passing the plates, the flat surface being wide enough to extend 65 from one needle to another, so that the plates

do not bob in and out as the needles pass. In coming in contact with these faces of the plates, the needles force the plates slightly back away from the stops 11, and as soon as the high needles pass the plates are forced 70 back again against the stops by the springs.

By the use of a finger for removing the loops from the points, I am enabled to make the loops very close together, and can, when desired, make a loop for each stitch, there being of course a point 4 for each needle 1.

I claim as my invention—

1. In a machine for making looped fabric, the combination of a needle cylinder, a dial or plate fitting within the needle cylinder, 80 stationary points carried by the dial plate, and a finger for moving the loops off of the points; substantially as set forth.

2. In a machine for making looped fabric, the combination of a needle cylinder, a dial 85 plate fitting within the needle cylinder, stationary points carried by the dial plate, and means for moving the points out of working position, and a finger for moving the loops off of the points; substantially as set forth. 90

3. In a machine for making looped fabric, the combination of a needle cylinder, a dial plate located within the needle cylinder, points carried by the dial plate, fingers for moving the loops from the points, and means 95 for moving the fingers out of working position; substantially as set forth.

4. In a machine for making looped fabric, the combination of a needle cylinder, a dial plate located within the needle cylinder, 100 points carried by the dial plate, fingers for moving the loops from the points, springs for holding the fingers in their working position, and means for moving the fingers out of working position; substantially as set forth. 105

5. In a machine for making looped fabric, the combination of a needle cylinder, a dial plate located within the needle cylinder, points carried by the dial plate, fingers for moving the loops from the points, springs 110 acting to hold the fingers in their working position, plates mounted on shafts, and having out-turned ends 15, stops 11 secured to the shafts and means for moving said plates and fingers; substantially as set forth. 115

6. In a machine for making looped fabric, the combination of a needle cylinder, a dial plate located within the needle cylinder, points carried by the dial plate, fingers for moving the loops from the points, springs 120 acting to hold the fingers in their working positions, plates connected to the fingers, and stops for limiting the inward movement of the fingers; said plates having flat surfaces 13^a, substantially as and for the purpose set 125 forth.

EDWARD MURBY.

In presence of—

CLARA G. EDWARDS,
A. M. EBERSOLE.
